TRASH RECEPTACLE

Loryn B. Deane and Edward V. Deane, both of
18 Overlook Road, Ardsley, N.Y. 10502

Filed Feb. 23, 1972, Ser. No. 228,786

Term of patent 14 years

Int. Cl. D7—06

U.S. Cl. D49—32

FIG. 1 is a top plan view of a trash receptacle showing our new design;

FIG. 2 is a front elevational view;

FIG. 3 is a rear elevational view; and

FIG. 4 is a right side elevational view.

We claim:

The ornamental design for a trash receptacle, as shown.
